C. W. ROYSE, OF PETERBOROUGH, NEW HAMPSHIRE.

Letters Patent No. 63,101, dated March 19, 1867.

IMPROVED TOWEL-RACK.

The Schedule referred to in these Letters Patent and making part of the same.

TO ALL WHOM IT MAY CONCERN:

Be it known that I, C. W. Royse, of Peterborough, in the county of Hillsboro, and State of New Hampshire, have invented a new and improved Towel-Rack or Bracket; and I do hereby declare that the following is a full, clear, and exact description thereof, which will enable others skilled in the art to make and use the same, reference being had to the accompanying drawings, forming part of this specification.

The present invention relates to a new and improved rack or bracket for towels, &c., which rack is to be fastened to the side wall or other desired part of the room, and is of such a construction that it can be so adjusted and set as to project in any desired angle or direction from the side of the room, and also be susceptible of being swung up into a vertical position against the wall when not in use, and thus out of the way.

In accompanying plate of drawings my improved towel-rack is illustrated—

Figure 1 being a plan or top view of the same; and

Figure 2, a transverse section taken in the plane of the line xx , fig. 1, showing it as secured to the side of a room.

Similar letters of reference indicate like parts.

A, in the drawings, represents my improved rack or bracket for towels, &c., which consists of a frame, B, formed of two end pieces, C, joined together by cross-bars or rails, D, running in directions parallel to each other, by one, D^2 , of which it is hung in and to the projecting pieces, E, of a plate F, for fastening them to the side of the wall of a room. On the bar D^2 , between the projecting pieces, E, is loosely hung an arm, G, that, by means of a set or thumb-screw, H, passing through it, can be made fast or secure to the said bar D^2 , this arm G forming a stop to the downward swing of the frame B upon the pieces E, by coming to a bearing against the plate F, of which said pieces E form a part. As the arm G is secured to the bar D^2 by a thumb-screw, H, it is plain to be seen that its position can be adjusted at pleasure, and thus enable any desired angle or direction of the frame C, when swung down, to be obtained, while at the same time the frame can be freely swung into a vertical position, or nearly so, against the side of the room, and thus out of the way if not in use or to be used.

I claim as new, and desire to secure by Letters Patent—

The frame C, hung in projecting pieces E, of a block or plate F, in combination with the arm G, having set or thumb-screw H, substantially as and for the purpose described.

C. W. ROYSE.
